UNITED STATES PATENT OFFICE.

JOHN LAMBERT OLSON, OF ST. PAUL, MINNESOTA.

STREET OR STATION INDICATOR.

1,094,743.

Specification of Letters Patent.

Patented Apr. 28, 1914.

Application filed December 18, 1911. Serial No. 666,320.

To all whom it may concern:

Be it known that I, JOHN LAMBERT OLSON, a citizen of the United States, residing at St. Paul, in the county of Ramsey and State 5 of Minnesota, have invented certain new and useful Improvements in Street or Station Indicators; and I do hereby declare the following to be a full, clear, and exact description of the invention, such as will enable others skilled in the art to which it 10 pertains to make and use the same.

This invention relates to improvements in street or station indicators—one object of the invention being to so construct the machine 15 that it can be operated automatically to shift the ribbon containing the names of streets or stations, and so that an electric motor can be utilized to project the ribbon or sheet step - by - step or to continuously 20 wind more or less of said ribbon or sheet from one roller to another.

A further object is to provide means for insuring freedom of rotation of the roller onto which the ribbon is being wound, and 25 for applying limited resistance to the rotation of the roller from which the ribbon is being unwound, whereby said ribbon will be maintained taut under all conditions.

A further object is to so construct an 30 electrically operated street or station indicator that, by manipulation of a single shaft, the various instrumentalities for controlling the movement of the ribbon which contains the names of the streets or stations, shall be 35 simultaneously reversed.

A further object is to so construct a street or station indicator that the use of spring 40 motors shall be obviated, and so that the accurate and easy operation of the machine, without strain on the ribbon, shall be insured.

With these and other objects in view, the invention consists in certain novel features of construction and combinations of parts 45 as hereinafter set forth and pointed out in the claims.

In the accompanying drawings; Figure 1 is a front elevation of the indicator; Fig. 2 is a side view; Fig. 3 is an enlarged front 50 view partly in section, with the casing removed, and showing the mechanism; Figs. 4 and 6 are right and left side views of the mechanism; Fig. 5 is a vertical sectional view through the center of the mechanism 55 looking toward the side shown in Fig. 4; Fig. 7 is an enlarged detail view partly in

section and partly in elevation; Fig. 8 is an enlarged sectional view showing the circuit shifting devices and adjacent parts; Figs. 9 and 10 are enlarged detail views illustrating 60 the clutch devices. Fig. 11 is a diagrammatical view of the circuits and Fig. 12 is a detail view of the trolley devices.

1 represents a suitable base, to which uprights 2—3 are secured and these, together with transverse rods 4 extending from one upright to the other, constitute the frame which supports various mechanisms hereinafter described. Winding rollers 5 and 6 are disposed between the uprights and on 70 the latter, suitable ball bearings are provided for these rollers. The ribbon or sheet 7, which bears the names of the streets or stations, passes from one of these rollers and winds upon the other (as hereafter explained) and said ribbon or sheet also passes over guide rollers 8—9 mounted in ball bearings, between the uprights 2—3. The ribbon or sheet 7 also passes over an upper roller 10 with which certain 80 devices coöperate to control the feeding movements of the ribbon to expose the names of streets thereon, one after another, in front of a slot 11 in the front of the casing. In order that passage of the ribbon over the 85 roller shall accurately rotate the latter to insure the proper action of the controlling devices above referred to, said roller is provided with sprocket wheels 12 and the ribbon is provided near each of its side edges 90 with perforations to engage over the sprockets of said wheels. To insure such engagement of the ribbon with the sprocket wheels, guide wheels 13 are provided. These guide wheels are mounted (preferably on 95 ball bearings) in frames or carriers 14 which are movably mounted on the frame and provided with handles 15, by means of which they can be raised to permit the placing of the ribbon over the roller 10 and 100 the sprocket wheels thereon. Each frame or carrier 14 is provided with a lug 16 projecting below the handle and against this lug, a spring 17 secured to the frame, bears for the purpose of insuring uniform pressure of the guide rollers upon the ribbon where the latter passes over the sprocket 105 wheels.

The journals of the winding rollers 5 and 6 are extended beyond the upright 2 of the 110 frame and form shafts 18—19, on which intermeshing gear wheels 20—21 are loosely

mounted. The upper gear 21 receives motion from the gear 20 and the latter receives motion from a pinion 22. A gear 23 is rotatable with the pinion 22 and receives motion from a pinion 24, the latter being rotatable with a gear 25 which receives motion from a pinion 26 on the armature shaft of an electric motor 27. Thus it will be seen that when the electric motor is operated, motion will be imparted through the gearing above described to the gears on the shafts of the winding rollers. Only one of the winding rollers will be positively driven by the motor at any time,—viz. the roller on which the ribbon is being wound, and to enable one or the other gear 20 or 21 to positively drive the winding roll with which it is connected, clutch devices *a*—*b* are employed. To this end, each gear 20 and 21 is provided with a hub or flange 28 embraced by a clutch band 29 provided at its ends with lugs 30—31. The clutch band is also provided with a lug 32 secured by means of a screw 33 to a lug 34 on a disk or collar 35 securely keyed to the shaft 18 or 19 as the case may be. The clutch bands are also provided with lugs 36, to which levers 37 are pivotally connected, the long arms of said levers being in position to be engaged by cones 38 movable on the shafts 18—19, and the short arms 39 of said levers being in position to engage levers 40 disposed at right angles thereto. A bolt 41 passes through holes in the lugs 30—31 of each clutch band and to the upper end of each bolt 41, one end of lever 40 is pivotally connected. Each lever 40 is provided near its pivotal connection with bolt 41, with a toe 42 which bears upon the adjacent clutch band lug 30. From this construction and arrangement of parts, it will be seen that when one of the cones 38 is moved toward the adjacent clutch, it will, by engagement with the lever 37, turn said lever on its pivotal support and cause its short arm 39 to depress the lever 40, causing the latter to turn on its support on clutch band lug 30 and draw upon the bolt 41 to clamp the clutch band on the flange or hub 28 and thus secure one of the gear wheels 20 or 21 to its shaft, so that the motor will be caused to positively drive the winding roller to which such gear wheel is thus secured. When one gear 20 or 21 is clutched to its shaft, the other gear wheel will be free on the shaft and means are provided for simultaneously opening one clutch and closing the other when the direction of operation of the driving means is reversed when it is desired to reverse the direction of travel of the ribbon or sheet which contains the names of the streets or stations. The devices for accomplishing these results comprise a lever 47 pivotally supported between its ends by an arm or bracket 48 on the framework, the

oppositely disposed arms of said lever being bifurcated to embrace the cones and provided with suitable pins to enter the grooves of said cones. The lever 48 is also provided centrally with an arm 49, with the free end of which, one end of a rod 50 is connected,—the upper end of said rod being connected with the strap 51 of an eccentric 52 keyed to a shaft 53. This shaft passes through the framework and is provided at 75 one end (beyond the casing) with a handle 54 by means of which it may be turned for the purpose of shifting the clutches *a* and *b* and for other purposes which will be hereinafter explained. In order to retain the 80 shaft 53 in the position to which it may be moved, spring-pressed dogs 55 may be employed for limiting the movements of the handle. It is apparent that when the handle is moved, the shaft 53 will be turned and that motion will be imparted by the eccentric 52 and the connections between the latter and the cones 38 to shift the clutches and thus clutch one winding roller to its gear and unclutch the other winding roller from 85 its gear.

When one winding roller is winding the ribbon thereon and therefore pulling it from the other winding roller, it is desirable that slight resistance shall be offered 95 to the rotation of the roller from which the ribbon is being unwound and yet permit the roller on which the ribbon is being wound to rotate freely, so that under all conditions and regardless of the relative amounts of 100 tape on the two winding rollers, the ribbon shall be maintained taut without danger of undue strain on the tape. For this purpose, brakes *c*—*d* are provided for the shafts 105 of the respective winding rollers, and devices actuated from the controlling shaft 53, are employed for applying one of said brakes and simultaneously releasing the other brake. These brakes and their actuating means, will now be explained. The 110 shaft of the roller 5 is extending beyond its bearing in the upright 3 and provided with a brake wheel 57. Brake jaws 58—59 embrace the brake wheel 57 and to the brake jaw 58, one end of a lever 60 is pivoted, said lever being pivotally attached between its ends to an arm 61. A weight 62 is attached to the lever 60 and acts to normally clamp the jaws to the brake wheel with sufficient power to retard the rotation of the winding drum, but without offering undue resistance to such rotation. The brake *d* for the upper winding roller is precisely the same as the brake *c* above described, and the same reference characters may be applied thereto. The controlling shaft 53 is provided, near the upright 3 of the framework, with two oppositely disposed eccentrics 63—64, and with these eccentrics, pivoted levers 64—65 115 co-operate. The outer arm of the lever 64 120

130

is connected, by means of a rod 66 with the weighted lever 60 of the brake *c* and the outer end of the rod 65 is connected by means of a rod 67 with the weighted arm 60 of the brake *d*. Thus it will be seen that when the shaft 53 is turned to shift the clutches *a* and *b*, the eccentrics 62—63 will be operated to release the brake from one winding roller and apply the brake to the other winding roller.

The journals of the roller 10 are extended beyond their bearings in the standards 2—3 of the framework and to these journals, disks 68 are secured and each of these disks is provided with a plurality of notches 69 (three being shown in each disk), each of said notches being approximately one inch in length and forming a shoulder 70 at one end. Two solenoids 71 are secured to the framework above the disks 68 and the cores 72 of these solenoids are pivotally connected to pivoted arms 73, each of the latter being provided with a tooth 74 to engage the shoulders 70 of the adjacent disk 68. The cores of the solenoids are normally pressed in a direction to insure the engagement of the teeth 74 of arms 73 with shoulders 70 of the disks 68, by means of springs 75 in the solenoid bobbins. An air pot 76 is located near each solenoid and the plungers of these air pots are connected by rods 77 with the arms 73 for retarding the movement of the latter in both directions, for a purpose hereinafter explained.

The arms 73 are provided, respectively, with switch arms 78—79, the construction of each of which is the same. Each switch arm has secured thereto, a block 80 of insulating material having sockets in which springs 81 are located. These springs operate to press a contact plate 82 mounted on said block into close contact with contact heads 83—84 on the ends of binding posts 85—86 carried by an insulating block 87 secured to the framework. The contact plate on the switch arm is guided and prevented from displacement by means of pins 88 secured to said plate and passing through the block 80 and switch arm and insulated from the latter.

A block 89 of insulating material is secured to the standard 3 of the framework by means of arms or braces 90, and this block carries two contact rings 91 and 92 each provided with suitable binding posts. The insulating block also supports contact heads 93—94, 95—96 and 97 and 98, each of said heads being provided with a suitable binding post.

A switch arm 99 is secured centrally between its ends to the shaft 53 and parallel with the block 89. This switch arm carries a plurality of spring-pressed brushes to cooperate with the contact devices carried by the block 89, and each brush is suitably

insulated from the switch arm. Thus the switch arm 99 is provided with brushes 100—101 to coöperate with the contacts 93—94 and 95—96 and these brushes are electrically connected by a short conductor 70 102. Brushes 103—104 are electrically connected by a conductor 105 and coöperate with the contact ring 91 and contact head 98, and brushes 106—107 are electrically connected by a conductor 108 and engage 75 the ring 92 and contact 97 respectively.

A brake 109, the same in construction as the weights hereinbefore described, coöperates with the armature shaft of the motor and is normally applied by the action of a 80 weight 110. The core 111 of a solenoid 112 is connected with the weighted lever 113 of the brake 109.

The contact rings 91 and 92 are connected, respectively, with the field terminals of the 85 motor 27, by means of conductors 114 and 115 connected with binding posts under said rings. One terminal of the brake solenoid 112 is connected with an armature terminal of the motor by a conductor 116, and the 90 other solenoid terminal is connected, by a conductor 117, with the contact 98. The other armature terminal is connected by a conductor 118 with contact 97. A line conductor 119 is connected at one end with the 95 line leading from the trolley to the motors which operate the car, preferably in rear of the fuses commonly employed in the motor circuit, and at its other end the conductor 119 is connected with the contact 95. 100 The contact 96 is connected, by a conductor 120 with contact 85 of switch 79, and the contact 84 of this switch is connected, by a conductor 121 with the switch ring 91 through the medium of a binding post under the latter. This same binding post is connected by a conductor 122 with contact 84 of switch 78, and the contact 85 of this switch is connected, by a conductor 123, with contact 93, and contact 94 is connected, 105 by a conductor 124 with the line conductor 119. A conductor 125 is connected at one end with the contact ring 92, and at the other end with one end of a resistance element 125^a, the other terminal of the latter being grounded by a conductor 125^b. The solenoids 71 are included in parallel between the ground conductor 125 and a conductor 126, the latter being connected with a contact arm 127 on the trolley pole. 110

A contact arm 128 is mounted on the cross wire 129 from which the trolley wire 130 is suspended and is held in position to be engaged by the lateral contact arm 127 on the trolley pole, by means of a weighted 125 arm 131. The lateral contact arm 127 is protected and prevented from being engaged by the contact arm 128 should the trolley wheel 132 leave the trolley wire, by means of a lateral frame 133 secured to 130

the trolley pole. It will of course be understood that the contact arms 128 will be located at the street crossings or stations.

When a car passes a street crossing or station, the lateral contact arm 127 on the trolley pole will engage a contact arm 128, and a circuit will thus be closed temporarily between the trolley and ground and including the solenoids 71—71 in parallel. This circuit 5 may be readily traced from contact arm 128 to contact arm 127, to conductor 126, through solenoids 71—71 in parallel to conductor 125, through resistance 125^a and then by conductor 125^b to the ground. The solenoids 71 will promptly raise their cores and the arms 73 being retarded somewhat by the action of the air pots, thus moving the teeth 74 of said arms out of the notches 69 of the disks 68 and releasing the ribbon spacing 10 roller 10. Each air pot 76 is provided with a small port 134 and a larger port 135 and the notches 69 in the disks are, as before stated, made approximately one inch in 15 length. It may also be here stated that the notches in one of the disks 68 are arranged 20 reversely to the notches in the other disk 68, so that one of the latch arms 73 will co-operate with one disk to prevent rotation of the roller 10 in one direction, and the other latch arm 73 will co-operate with the 25 other disk to prevent rotation of the roller 10 in the reverse direction. Now, as the operation of the solenoids to raise the latch arms for releasing the roller 10, is momentary, it is necessary that said latch arms 30 shall not drop until notches of both disks 68 shall have passed the teeth of both latch arms. This is accomplished by the operation of the air pots. After the circuit of 35 the solenoids 71—71 shall have been opened by movement of the contact arm 127 past the contact arm 128, the springs will tend to force their cores and the latch arms downwardly, but such movement will be retarded 40 by the plungers of the air pots until the larger ports 135 in the latter have been passed by the plungers, when the latch arms will be permitted to quickly descend until their teeth 74 rest upon the peripheral portions 45 of the moving disks 68. When the disks shall have rotated sufficiently to bring other notches under the teeth of the latch arms, the latter will be forced quickly down and the disks 68 and the spacing roller will 50 be stopped. When the latch arms 73 were raised by the action of the solenoids 71, the switch arms 78—79 were caused to descend and electrically connect the contacts 84—85 with the result of closing the motor circuit 55 and thus causing the motor to operate the mechanism to move the ribbon. Such movement of the ribbon will continue until the switches 78—79 are again opened by the descent of the latch arms 73 when other 60 notches of the disks 68 move under the teeth 65

74 of said arms, as above explained. It will also be observed that when the motor circuit is closed, the motor brake 109 will be released by the action of the solenoid 112 and that as soon as the motor circuit is opened, 70 this brake will be at once applied by the weight 110 and the motor will be promptly stopped.

Let it be assumed that the main switch arm 99 is in the position shown in the drawings. Under such conditions, the motor circuits may be traced as follows when the switches 78—79 are closed: by line 119 to contact 95, to brush 100, to brush 101, to contact 96, by conductor 120 to contact 85 of switch 79, to contact 84 of said switch, then by conductor 121 to contact ring 91. At this point the circuit divides between the field and armature circuits of the motor, placing the same in parallel with each other. The armature circuit will be traced from ring 91 to brush 103, by conductor 105 to brush 104, then by conductor 117, through solenoid 112 and conductor 116 to one armature terminal; from the other armature terminal by conductor 118 to the contact 97, to brush 107, to brush 106 to contact ring 92. The field circuit will be traced from ring 91, to binding post under same, then by conductor 114 to one field terminal, and from the other field terminal, by conductor 115 to ring 92 by means of binding post under the same. The parallel motor circuits are thus connected with the ring 92 and the latter is grounded through conductor 125, resistance 125^a and 85 conductor 125^b. 90

When the shaft 53 is operated as hereinbefore described to reverse the direction of travel of the ribbon, the switch arm 99 will also be shifted so as to change the direction of current through the armature circuit of the motor and thus reverse the operation of the latter. When the armature circuit has been thus reversed, it may be traced as follows: from line 119, by conductor 124 to contact 94, to brush 100, by conductor 102 to brush 101, to contact 93, then by conductor 123 to contact 85 of switch 78, to contact 84, by conductor 122 to ring 91, to brush 103 by conductor 105 to brush 104 to contact 97 by conductor 118 to one armature terminal, from the other armature terminal through conductors 116—117 and solenoid 112 to contact 98, to brush 107, by conductor 108 to brush 106, then to contact ring 92 and finally to the ground line. From the above description, it will be readily understood that when the shaft 53 is turned, the clutches and brakes on the winding rollers will be shifted as before explained, and that simultaneously with such shifting, the electric circuits will be manipulated to reverse the motor 22 to reverse the direction of travel of the ribbon. 110

The ribbon may be of sufficient length to contain lists of streets of all the railway 130

lines of a city, so that the indicator may be adapted for use on any line on which it may be desired to run the car. It may be necessary therefore, at times to run a considerable amount of ribbon continuously from one winding roller to the other. To accomplish this, I employ the motor and provide circuit connections whereby the motor can be continuously operated. Thus I provide a circuit closer 136 operable by a push button 137. One arm of the circuit closer is connected by a conductor 138 with the conductor 126 and the other arm of said circuit closer is connected at 139 with the line 119. It will be apparent that when the circuit is closed at 136, the switch solenoids 71 will be energized by current from the line 119; the switches 78-79 will be closed and the motor will be operated continuously until the circuit is again opened at 136.

In order that the indicator shall denote the names of the transfer points of the various lines, I provide sheets or charts containing such data, and one of these sheets, 137^a is attached to the front of the casing by means of clips 138. Each chart 137^a has indicated thereon, the names of the transfer points on the line and also data stating with what lines transfers can be made at the various transfer points. The chart also contains a notice that all streets noted on the tape with a specified character, are transfer points, and the names of streets on the tape where transfer points are located, are marked with said character on the tape as illustrated in Fig. 1 of the drawing. It is desirable that the indicator shall be provided with means to denote the direction in which the mechanism is to run with respect to the direction in which the car is to run. To this end, I provide a sign or target 140 on which the words "East" and "West" or other direction indicating words are produced and one of these words will always be visible through a slot 141 in the front of the casing. The sign or target 140 may be made curved as shown in Figs. 6 and 10 and is provided with a brace 142 pivotally supported at 143. A curved arm 144 is fixed with relation to the sign or target and its brace and is movable with the same. The approximately horizontal portion of the arm is disposed under an eccentric 145 on the shaft 39, so that when shaft is turned to effect the various manipulations of the mechanism, as hereinbefore described, the cam 145, coöperating with the curved arm 144, will shift the sign or target.

It may be desired to provide an audible signal to attract attention of passengers to the operation of the indicator and thus denote when a street crossing or station is reached. This may be readily accomplished with the use of a buzzer 146 included in a local circuit 147 with a battery 148, said cir-

cuit also including contacts 149-150 which are bridged by a contact plate 151 carried by the arm 73.

Various slight changes might be made in the details of construction of my invention without departing from the spirit thereof or limiting its scope and hence I do not wish to restrict myself to the precise details herein set forth except as defined in the appended claims.

Having fully described my invention what I claim as new and desire to secure by Letters-Patent, is:—

1. In an indicator, the combination with two winding rollers, an electric motor and gearing between said motor and the winding rollers, of a spacing roller, a tape movable from one winding roller to the other and also passing over said spacing roller, a latch lever normally retaining said spacing roller stationary, an electro-magnetic device connected with the latch lever, a switch controlled by the latch lever, an electric circuit including the motor and said switch, another electric circuit including said electro-magnetic devices, means for momentarily closing said last-mentioned circuit to momentarily energize said electro-magnetic devices, an air pot, and connections between the plunger of the air pot and the latch lever, whereby the return of the latter toward the spacing roller will be retarded.

2. In an indicator, the combination with two winding rollers, a spacing roller, a motor, gearing between the motor and winding rollers, and a tape passing from one winding roller to the other and over the spacing roller, of disks on the spacing roller, each disk having a plurality of notches, pivoted latch arms to engage the notched disks, solenoids having spring pressed cores connected with said latch arms, air pots having their plungers connected with said latch arms, each air pot having a small air inlet near one end and a larger air inlet intermediate of its ends, whereby said latch arms can move freely to release the spacing roller when the solenoids are energized and be retarded in part of their return movement toward the locking disks after the solenoids have been deenergized, an electric circuit including the motor, an electric circuit including said solenoids, means for momentarily closing and then opening the last-mentioned circuit, and switches in the motor circuit controlled by the latch arms.

3. In an indicator, the combination with two winding rollers, a tape passing from one to the other, a motor and gearing between the motor and the winding rollers, of clutches for connecting the winding rollers to the gearing, a controller shaft, an eccentric thereon, cones on the shafts or journals of the winding rollers, connections between said cones and clutches, a lever pivoted be-

- tween its ends and connected with said cones, a central arm on said lever, and a connection between said arm and the eccentric on the controller shaft.
5. 4. In an indicator, the combination with two winding rollers, a tape passing from one to the other, a motor, gearing between the motor and said rollers, and means for connecting said rollers alternatively with 10 the gearing, of a brake for each roller, weights for applying said brakes, a controller shaft, two oppositely disposed eccentrics on said shaft, and devices intermediate of said eccentrics and the weights of 15 the brakes for releasing one brake or the other when the controller shaft is turned.

5. In an indicator, the combination with two winding rollers, a tape passing from one to the other, a motor for driving said rollers, and means for reversing the direction of rotation of the rollers, said means including a controller shaft, of an oscillatory slide or target, an eccentric on the controller shaft, and an arm movable with the sign or target and operable by said eccentric. 20 25

In testimony whereof, I have signed this specification in the presence of two subscribing witnesses.

JOHN LAMBERT OLSON.
